No. 659,446.

Patented Oct. 9, 1900.

L. D. LAWNIN.

URINAL.

(Application filed June 27, 1900.)

(No Model.)

Attest:-

Mr. Smith
E. S. Knight

Inventor:—
Louis D. Launin:—
Knight, Jr. atty's.

UNITED STATES PATENT OFFICE.

LOUIS D. LAWNIN, OF EDWARDSVILLE, ILLINOIS, ASSIGNEE TO THE N. O. NELSON MANUFACTURING COMPANY, OF ST. LOUIS, MISSOURI.

URINAL.

SPECIFICATION forming part of Letters Patent No. 659,446, dated October 9, 1900.

Application filed June 27, 1900. Serial No. 21,784. (No model.)

To all whom it may concern:

Be it known that I, LOUIS D. LAWNIN, a citizen of the United States, residing at Edwardsville, in the county of Madison and State of Illinois, have invented certain new and useful Improvements in Urinals, of which the following is a full, clear, and exact description, reference being had to the accompanying drawings, forming part of this specification.

The object of my invention is to provide for an adequate ventilation of the gutter and apartments of a urinal and to so form and arrange the parts that they can be easily and readily assembled or put together.

My invention consists in features of novelty hereinafter fully described, and pointed out in the claims.

Figure I is a front elevation showing the gutter-well in vertical section. Fig. II is an enlarged detail transverse section taken on line II'II', Fig. I. Fig. III is a detail perspective view showing the manner of supporting the back slabs of the compartments. Fig. IV is a detail perspective view showing one end of the gutter.

1 represents an elevated tank connected by a pipe 2 to a drip-pipe 3, from which water is drained to a gutter 4 along slightly-inclined back slabs 5, as usual.

6 are partition-slabs, which, with the slabs 5, form the compartments of the urinal.

7 are the floor-slabs between or on which the slabs 6 rest, the inner ends of the slabs 7 resting on strips 8, supported a short distance above the top of the gutter on blocks 9 to leave spaces 8^a for the passage of air. The blocks 9 are interposed between the strips and the top of the gutter. The inner ends of the slabs 7 do not extend quite to the slabs 6, there being spaces 10 left between the two for drainage and for the passage of air.

The slabs 5 are supported, as shown in Figs. I and III, by brackets or hangers 11, bolted or otherwise secured to the lower ends of the slabs 6, the hangers curving downwardly, as shown at 12, and their outer ends being turned upwardly, as shown at 13, so that they will receive and hold the slabs 5.

14 is a well or recess in which the gutter 4 is located. The gutter is supported on frames

15, the gutter having outturned top flanges 16, that rest upon the frames. I have shown a frame 15 at or near each end of the gutter; but more may be used, if desired.

17 represents a vent-pipe that connects with the well 14, preferably through a number of branches 18 and which extend to the outside of the building.

By referring to Fig. II it will be seen that there will be a free circulation of air from the gutter through the spaces 8^a, through the well 14, and out through the vent-pipe 18, and likewise there is a free circulation of air from above the slabs 7 down through the spaces 10, through the spaces 8^a, through the well 14, and out through the vent-pipe 18. The construction thus provides for a perfect ventilation of the gutter and the compartments.

20 represents the drain-pipe of the gutter, which is provided with a double trap 21 22, and 23 represents an air-pipe, forming a communication between the tank 1 and the space between the two traps 21 and 22, so that when air is exhausted from the space between the traps through the pipe 23 a siphonic action takes place to draw water from the gutter. This arrangement of double trap and air-pipe is well known, and I make no claim thereto, *per se*, as inventor.

24 is an overflow-pipe provided with a trap 25 and communicating with the bottom of the well 14 to drain off any water that may enter the well. The overflow-pipe has a branch 26, communicating with the gutter 85 through an opening 27 in the end of the gutter opposite that with which the drain-pipe connects.

The overflow-pipe 24 serves to receive all excess of water over the amount requisite to flush the gutter, and some of such excess or overflow water is constantly maintained in the trap 25 of the overflow-pipe to serve as a seal against the escape of odors to return to the gutter.

I claim as my invention—

1. In a urinal, the combination with a well or recess of a gutter adapted to hold a body of water and located in said well or recess, strips held a distance above the upper edges 100 of the gutter to provide air-spaces, the back slabs, the floor-slabs supported on said strips

and arranged to provide air-spaces between them and the back slabs of the urinal, a vent-pipe communicating with said gutter through said well, a trapped drain-pipe connected to 5 said gutter, and a trapped overflow-pipe also connected to said gutter, substantially as described.

2. In a urinal, the combination of a gutter adapted to hold a body of water and located 10 in a well or recess, strips held a distance above the upper edges of the gutter to leave air-spaces between them, floor-slabs supported on said strips and arranged to leave air-spaces between them and the back slabs

of the urinal, a vent-pipe communicating 15 with said gutter through said well, and a trapped drain-pipe connected to said gutter, substantially as and for the purpose set forth.

3. In a urinal, the combination of a gutter adapted to hold a body of water, a vent-pipe 20 communicating with said gutter, a double-trapped drain-pipe connected to said gutter, and a trapped overflow-pipe connected to said gutter, substantially as set forth.

LOUIS D. LAWNIN.

In presence of—

E. S. KNIGHT,
M. P. SMITH.
